ELECTROMAGNETIC THERAPEUTIC COMPRESS HEATING APPLIANCE

Filed Dec. 15, 1925

UNITED STATES PATENT OFFICE.

JOHN H. DEQUER, OF LOS ANGELES, CALIFORNIA.

ELECTROMAGNETIC THERAPEUTIC-COMPRESS-HEATING APPLIANCE.

Application filed December 15, 1925. Serial No. 75,567.

This invention relates to electromagnetic therapeutic compress heating appliances.

It is understood that in many cases of local pain, swelling and congestion, as well as in analogous classes of emergency, it is highly desirable to apply a compress locally to the portion of the human body affected, and while sometimes this may be a hot compress, at other times a hot compress may be applied alternately with a cooler one.

At any event, in the application of such compresses, there is required almost the constant attention of a nurse or attendant, as the attendant is required to replace a cooled-off compress with a hotter one at frequent intervals, so that much time is taken up from other duties in wringing out the cooled off compresses in hot water, for the application of the hot compresses.

One of the primary objects of my improvements has been to devise a simple and effective pad-like metallic heating appliance, which may be facilely applied to a wet compress for maintaining the same substantially at a constantly uniform heat, and which may be readily removed as desired to allow the compress to become cold, or applied to the cold compress to heat the same up, without the necessity of wringing out the compress in hot water to raise its heat to the desired degree.

I have also found that by the establishing of a rather intense magnetic field or fields, in the zone of the compress, such auxiliary vibratory magnetic treatment has a very soothing and curative effect, especially in the case of colic from whatever source, as well as in cases of congestion such as exist in pneumonia, or analogous conditions, and in various other instances of local pains, swellings and congestions from numerous causes. A further object of my improvements, therefore, has been to devise such an appliance that the heating medium thereof additionally functions to establish a rather intense vibratory magnetic field or fields substantially covering or encompassing the entire heating zone, and thus coating with the moderated heat generated, for soothing and otherwise beneficial effects.

In the accomplishment of the foregoing and other objects, features and advantages of the invention, all of which will more fully appear as incidental to the following disclosure, the improvements broadly embody a pad-like shallow metallic casing that

houses suitably coiled and mounted insulated wiring, functioning primarily as a moderated heating agency, for local application to the body of a patient through an interposed compress, and which coiled wiring additionally functions as a means for establishing an intensive magnetic field or fields, at such locally applied position, when a suitably stepped-down alternating current is caused to flow therearound.

With these general outlining remarks, although various features in detail will hereinafter appear, reference will now be immediately had to the accompanying drawings, illustrating a practical embodiment of the improvements, in which drawings—

Figure 1 is a diagrammatic view of one form of coiled wiring which may be employed with the appliance; Figure 2 is a top plan view of the appliance with its upper wall removed; Figure 3 is a cross-sectional view, partly in elevation, taken substantially along the line 3—3 of Figure 2; and Figure 4 is a cross-sectional view taken locally through one of the coils, and showing the means for mounting the same within the heater casing or housing.

The numerals 5 and 6 respectively designate relatively thin top and bottom walls of a shallow metallic casing or housing, which walls are preferably in the nature of diaphragmatic circular discs, although they may be of other shapes than circular, and may have their peripheral edge portions turned in the form of marginal spacing rims 7 and 8, adapted for snug seating relation as indicated at 9.

This casing is adapted to house suitably disposed coiled insulated wiring, in the form of a multi-strand fine cable of soft copper wires, so mounted as to function both as a moderated heating means and as a means for establishing an intensive magnetic field or fields, as has hereinbefore been stated and which features will hereinafter more fully appear as to details, and for the facile handling of this metallic pad-like electromagnetic heater, the same is preferably equipped with a handle unit that is flexibly mounted in resilient connection with said casing, being adapted to additionally function as a junction conduit, providing a control switch, for housing the circuit wires connecting said coiled wiring of the device with the line wires of an outside alternating current source, such as the usual house lighting cir-

cuit, with substantial resistance means interposed in the circuit, for stepping down the alternating current, and which resistance means preferably embody the coils of an improved type of electromagnetic blanket, with which this present appliance may be most satisfactorily used, such a type of blanket of itself being claimed in a prior application filed by me on November 28, 1924, under Serial No. 752,782, and also fully disclosed in an application subsequently filed by me on July 26, 1926, under Serial No. 125,048.

For the secure attachment of this handle unit, a complementary pair of recesses may be formed in the rims 7 and 8 of the casing, at the positions indicated at 10, for the reception of the hollow open-ended shank, lug or nipple 11, of a cast metal support, the 20 lower portion of which may be formed with an offset inwardly projected seating base 12, for soldering or otherwise securing to the inside face of the bottom wall 6 of the casing, and the outer portion of which 25 nipple may be formed with a shoulder and a reduced peripherally grooved end 13, for snugly seating the inner end coil or coils of a substantially stiff elongated coil spring 14. The outer end coil or coils of the spring 30 14 are analogously attached to and firmly supported by the inner end of a standard snap switch casing 15, the specific means shown for this support being a tubular element 16 embedded in that end of the switch 35 casing, and the outer end of said switch casing analogously mounts the inner end of a second substantially stiff coil spring 17, the outer end of which latter may be provided with a fibre bushing 18. Through 40 this junction conduit handle unit is passed a short lamp cord extension 19, in circuit with the switching elements of the electric snap switch casing 15, the inner ends of which lamp cord connection are adapted to 45 be connected in circuit with the coiled wiring of the heater device, and the outer ends of which lamp cord connection carry the female element 20 of a plug socket connector, adapted for plugging in with the coils 50 of said improved type of blanket, as the resistance means, although the device could be employed with other types of blankets, or even with other forms of resistance means interposed in the circuit.

As a matter of broad principle it may be that the coiled wiring of the heater device could be arranged as a single continuous coil, especially if its convolutions were conically wound, or as several coils in different 60 arrangement than as actually shown, although as a matter of preferred structure I have found it most desirable to provide a central coil encompassed by an auxiliary series of individual coils, in a multi-coil arrangement and whether or not these indi-

vidual auxiliary coils have approximately the same or a greater or a less length of wiring than the central coil, whereby individual magnetic fields may be established to collectively embrace the entire zone or area of the heater.

The coils of this auxiliary series may be so wound as to establish magnetic fields of the same disposed polarity relatively to each other, but of opposite polarity with reference to the central coil; or of the same polarity with reference to the central coil; or of alternately opposite polarity relatively to each other, when some of them would be of the same and others of opposite polarity 80 relatively to the central coil; or as actually shown in the drawings, simply by way of general illustration, some of the successive auxiliary coils may be wound in the same direction relatively to each other, while other 85 of the successive auxiliary coils may be wound in an opposite direction relatively thereto, but in the same direction as the central coil.

Following this latter arrangement, the drawings show successive auxiliary coils 21, 22, 23 and 24 as being wound to the right, or in a clockwise direction, while the larger central coil 25 and the remaining successive auxiliary coils 26 and 27 are shown as being 95 wound to the left, or in a counter-clockwise direction. Furthermore, in the drawings, the central coil 25 is shown as being interposed between the auxiliary coils 24 and 26, with the auxiliary coil 27 at the end of 100 the series, but obviously the coil 27 could be directly connected with the coil 24, and the central coil 25 disposed at the end of the series, for direct connection with one of the lamp cord wires 19, instead of as actually 105 shown, the other lamp cord wire being connected with the coil 21.

It is to be particularly noted that I prefer to form these coils with a dual winding, for intensifying the magnetic effect; that is 110 to say that a short length 28 of the insulated wiring is a single cable of fine copper strands, covered with insulation, connected with a longer length 29 thereof in the form 115 of a double cable of analogous texture.

The connection between these single and double cables of the individual coils, as indicated at 30 of Figure 1, as well as the connections 31 between the cables of the successive coils, are preferably made by twisting together the exposed complementary ends of the strands of the cables, for a short distance, and applying a binding solder to these twisted together ends, for encompassing the same as an embedding coating, 120 whereby so-called cool connections are made, or ones that do not become overheated or disconnected. These connections may be covered with insulating tape, as indicated 125 at 32 of Figure 2, and the same form of 130

connections may also be made between the free ends of the terminal coils of the series and the lamp cord wires 19, as indicated at 33.

5 In this multi-coil arrangement, the insulated wiring is separately wound around metallic spools 34 having a tubular iron core 35, functioning as electromagnets, the ends of the cables being complementally connected together thereafter as before described, and these magnet spools may be supported within the heater casing in any suitable way. However, as the coils are separately wound around their respective supporting spools, and thereafter connected in circuit, it is preferable to detachably mount the same within the heater casing.

To this end, the spools of the coils 21, 22, 23, 24 and 27 are shown as being detachably mounted on the bottom 6 of the casing by means of inverted bent springs 36, having their base or apex soldered to said bottom, as at 37 Figure 4, or otherwise secured thereto, the upstanding arms of said springs being adapted to project up through the tubular core 35, of its complementary magnet spool, with either or both of said upstanding arms terminating with a hooked end for clasping over the upper edge of the core. The spool of the central coil 25 and of the auxiliary coil 26, however, show another means of mounting the spools, in conjointly supported relation, by means of the arms 38, the spring element 36 being adapted for projection up within the tubular core of the coil 26, as heretofore described, and the tubular core 35 of the central spool being firmly held and centered between the top and bottom walls of the heater casing, by means of the axially disposed binding screw 39, which securely holds the upper and lower sections of the heater casing in assembled relation. As a matter of fact, all of the auxiliary spools may be mounted in substantially the same manner by means of a framework having radiating or spider-like arms carrying the springs 36 for holding the spools in properly spaced relation and as detachably mounted, and the central portions of the top and bottom walls of the casing may be formed with inward depressions, not appearing in the views, forming projections extending into the ends of the tubular core of the central spool, as centering studs therefor.

From all of the foregoing it is believed that the novel features, functioning and advantages of the improvements will be fully apparent, but while I have thus set forth the preferred structures, as they now occur to me, it will nevertheless be obvious that some alterations could be made, without departing from the spirit of the invention, and accordingly it is to be understood that I do not wish to unnecessarily

restrict myself to all of the details exactly as disclosed, excepting as they may come within the terms of the claims, or the equivalent of their elements and combinations thereof, or as fairly interpreted in the light of the specification if necessary.

What I do claim, as new and patentable, is:—

1. In therapeutic compress heating appliances, the combination of a shallow casing embodying spaced top and bottom walls, coiled insulated wiring so housed within said casing as to provide for establishing an electromagnetic heating zone entirely and uniformly therearound, a junction conduit handle unit for said casing in open communication therewith, and electrical circuit leads extending from the terminal ends of said coiled wiring and through said handle unit to the exterior of said casing. 85

2. In therapeutic compress heating appliances, the combination of a shallow casing embodying spaced top and bottom walls, coiled insulated wiring so housed within said casing as to provide for establishing an electromagnetic heating zone entirely and uniformly therearound, a junction conduit handle unit for said casing that embodies coiled spring means as a part thereof and is in open communication with said casing, and electrical circuit leads extending from the terminal ends of said coiled wiring and through said handle unit to the exterior of said casing. 90

3. In therapeutic compress heating appliances, the combination of a shallow casing embodying spaced top and bottom walls, coiled insulated wiring so housed within said casing as to provide for establishing an electromagnetic heating zone entirely and uniformly therearound, a junction conduit handle unit for said casing that embodies a pair of coiled springs with an interposed electrical switch as elements thereof, the said handle unit being in open communication with said casing, and electrical leads extending from the terminal ends of said coiled wiring and through said handle unit, in circuit with said switch, to the exterior of said casing. 115

4. In therapeutic compress heating appliances, the combination of a shallow closed pan-like casing embodying spaced top and bottom walls, coiled insulated wiring so housed and mounted within said casing as to provide for establishing an electromagnetic heating zone entirely and uniformly therearound, which arrangement embodies a central coil and auxiliary encompassing coils individually wound around separated spools of magnetic material, the said coils being connected in series, and electrical circuit leads extending from the free ends of the terminal coils of the series to the exterior of the casing. 120

5. In therapeutic compress heating appliances, the combination of a shallow closed pan-like casing embodying spaced top and bottom walls, coiled insulated wiring so
5 housed and mounted within said casing as to provide for establishing an electromagnetic heating zone entirely and uniformly therearound, which arrangement embodies a
10 central coil and auxiliary encompassing coils individually wound around separated spools of magnetic material, the said coils being

connected in series and some of said auxiliary coils being wound in a direction opposite to the direction of winding of said central coil, to provide for magnetic fields of opposed polarity, and electrical circuit leads extending from the free ends of the terminal coils of the series to the exterior of the casing.

In testimony whereof, I affix my signature. 20

JOHN H. DEQUER.
